his attorneys

UNITED STATES PATENT OFFICE

134,992

DESIGN FOR A BILLBOARD

Marvin G. Peters, Pittsburgh, Pa., assignor to Pittsburgh Outdoor Advertising Company, a corporation of Pennsylvania

Application December 5, 1942, Serial No. 108,950

Term of patent 7 years

To all whom it may concern:

Be it known that I, Marvin G. Peters, a citizen of the United States, residing in Pittsburgh, in the county of Allegheny and State of Pennsylvania, have invented a new, original, and ornamental Design for Billboards, of which the following is a specification, reference being had to the accompanying drawing, forming part thereof.

Fig. I is a view in perspective. Fig. II is a view in end elevation of a billboard showing my new design.

I claim:

The ornamental design for a billboard, as shown.

MARVIN G. PETERS.
